Range finders—Case T.	608,186	Oct. 29, 1943	Do.

The purpose of the present invention is to give increased sensitivity in any of the range correction setting or autocollimating systems described in the above listed cases. The present invention is useful with and described in connection with coincidence range finders, short base range finders, ortho-pseudostereo range finders, stereo range finders, range correction setting systems, pure autocollimating systems, coincidence line and fiducial mark systems, single observer instruments, auxiliary observer instruments and in combination with the methods described in Cases M and N which also give increased sensitivity.

It is an object of one embodiment of the invention to give an extremely stable coincidence in line and fiducial mark arrangement useful in either coincidence or stereo range finders.

Fundamentally, the increase in sensitivity by the present invention is gained by sending the collimator light beam, described repeatedly in other cases in this series, back through the range finder optical system for at least one extra trip. The invention is most easily described with respect to a range correction system and hence is so described although it is applicable to the other systems. One of the test marks (more generally called adjustment coincident elements) is located in one of the comparison planes or so that a virtual image thereof is in this plane. Means are provided for projecting light from this element at least twice through the optical

system to form an image thereof adjacent to the other element which is in the same comparison plane or in the other one. Of course, in coincidence range finders the comparison planes are coplanar. The projecting means includes in one of the comparison planes a reflector with at least two reflecting surfaces. A triple mirror with its apex optically in the comparison plane or at least a dihedral reflector with its roof edge vertical and optically in the comparison plane is satisfactory.

Since the element light beam traverses the range finder optical system twice, anything which affects the light beams from the object being ranged, doubly affects the element light beam. This results in double sensitivity and thus makes it easier to bring the range correction setting marks into coincidence.

By having at least two such reflector systems, one in each comparison plane, the element light beam may be reflected back and forth through the optical system, increasing the sensitivity in proportion to the number of trips, until ultimately the light loss is so great that no useful image is formed. If the element light beam traverses the system an even number of times, the adjustment coincident elements are, of course, in the same comparison plane whereas they are in opposite comparison planes when the light beam makes an odd number of trips.

In combining this case with Case M it is possible to have the relayed images viewed stereoscopically and compared with the elements themselves. This is similar to Case M in that the instrument is in adjustment when the apparent image distance is the same as the apparent element distance.

The invention and its objects will be fully understood from the following description when read in connection with the accompanying drawings, in which:

Fig. 1 is a plan view of a coincidence range finder incorporating a simple embodiment of the invention, Fig. 1A being a view through the eyepiece of the instrument;

Fig. 2 is a schematic showing of the optical system of Fig. 1;

Fig. 3 is a similar schematic showing of a somewhat more elaborate embodiment;

Fig. 4 shows an embodiment of the invention applied to stereo range finders, Fig. 4A being the binocular field of view through the instrument;

Fig. 5 shows a similar embodiment in which the element light beams originate in a third plane and are viewed in a fourth plane by an

auxiliary observer, Fig. 5A being the field of view of the auxiliary observer;

Fig. 6 shows a stereo range finder incorporating the combination of the present invention with the mutual nodal focal plane system, Figs. 6A and 6B being enlarged views of details of the arrangement and Figs. 7A and 7B being the binocular fields of view of the main and auxiliary observers;

Fig. 8 shows the application of the invention to a range finder of the type described in Case L of this series, Fig. 8A being the field of view;

Figs. 9 and 9A show an alternative embodiment of one detail of Fig. 4;

Figs. 10, 10A, 11 and 11A show alternative embodiments of a detail of Fig. 1;

Fig. 12 shows a short base range finder incorporating a pure autocollimating form of the invention, Fig. 12A being the field of view;

Fig. 13 shows a stereo range finder incorporating a coincidence line and fiducial mark form of the invention, Fig. 13A being the field of view of an auxiliary observer and Fig. 13B being an enlarged view of the coincidence line and fiducial mark element;

Figs. 14, 15 and 16 show a detail of a preferred embodiment of the invention which may be incorporated either in the coincidence range finder of Fig. 1 or the stereo range finder of Fig. 4.

In Fig. 1 light from the object being ranged is received on mirrors 20 arranged to form optical squares and is brought to focus by objectives 21 and prisms 22 and 23 to form images in coplanar comparison planes 24 to be viewed through an eyepiece 25. Coincidence of the range finder images is adjusted by a light deviator 26 located in one of the object beams. According to the invention, light from a lamp 30 is reflected by prism 31 to illuminate a range correction setting mark 32. Light from this mark is reflected by the prism 23, collimated by the right-hand objective 21 and is picked up by small prism 33 which is not quite an optical square, but which reflects the light to a similar small prism 34 at the other viewing point of the range finder. This light is then reflected back into the optical system of the range finder and brought to focus in the comparison plane 24. However, just before it comes to focus, the light strikes a porro prism 35 having its roof edge vertical and optically in the comparison plane 24, and is reflected back through the optical system, to be collimated, to be reflected from one viewing point to the other and to be brought to focus to form an image 36 adjacent to fiducial marks 37 in the comparison plane. As long as the instrument stays in proper adjustment the image 36 falls between the two diamond shaped parts of the mark 37. If the instrument is out of adjustment for any reason, this may be corrected by a light deviator or zero adjuster 38 which affects both the outgoing and returning element beam and also affects one of the beams from the object being ranged.

This optical system or at least the effect thereof is shown schematically in Fig. 2. The purpose of such a schematic showing is quite apparent when one attempts to consider more complicated systems. In fact, such a system having five times normal sensitivity is similarly shown in Fig. 3 wherein light from a lamp 40 reflected by a prism 41 illuminates an adjustment coincident element 42. A pair of dihedral reflectors 43 and 44 in the coplanar comparison planes send this light beam back and forth through the

range finder optical system until ultimately it comes to focus forming an image 45.

In Fig. 4 light beams from the object being ranged are received by optical squares 50 and brought to focus by objectives 51 in stereo comparison planes 52 in which are located field lenses. The stereo images are viewed through optical systems including dihedral reflector 53, relay lenses 54, adjustable rhombs 55 and eyepieces 56. The apparent object distance is adjusted by a light deviator 68 located in one of the object beams. According to the invention light from a lamp 60 is reflected by a semi-transparent reflecting surface 61 to illuminate a vertical mark 62. This mark itself is viewable through the semi-transparent surface 61 by the right eye of the observer. Preferably, however, a similar mark located on a totally reflecting surface 67 is illuminated through the semi-transparent surface 61 and light from this auxiliary mark is reflected by the semi-transparent surface 61 to the observer's eye. In either case, the right eye of the observer sees a standard mark with which he must compare an image 66, which is an image of the mark 62 produced by light collimated by the objective 51 reflected from one viewing point to the other by penta-prisms 63 and 64 and reflected back through the whole system by a porro prism 65 located in the other comparison plane. If the image 66 is not in coincidence with the original mark 62 or other standard mark seen with the right eye of the observer, due to maladjustment of the instrument, this may be corrected by means of the zero adjuster 69.

In Fig. 5 light from the object being ranged is directed by penta-prisms 70 through objectives 71 into focus on field lenses 72 to be viewed as in Fig. 4. In this case, however, the collimator beam is provided by a lamp 75 which illuminates a mark 76 and the light therefrom is collimated by a lens 77. This light is reflected by penta-prisms 78 and 79 at the viewing points of the instrument into the range finders to come to focus in the comparison planes and to be reflected by porro prisms 80 and 81 there located. The reflected beams are picked up by penta-prisms 82 and 83 and brought to focus by a lens 84 to form images 85 which may be viewed through an eyepiece 86. The field of view of an auxiliary observer is shown in Fig. 5A. As before, coincidence of the images 85 may be obtained by adjusting a zero adjuster 69. Since the prisms 78 and 79 act as a beam splitter, the mark 76 constitutes both elements of the pair of adjustment coincident elements or the upper half of the mark 76 is one element and the lower half is the other.

In Figs. 6 to 7B a corresponding system is shown in which light from lamps 90 is reflected by half silvered surfaces to illuminate adjustment coincident elements 91. That is, the upper half of this surface is semi-transparent. These elements 91 are in the nodal planes of lenses 92 separated by their focal length so that each lens collimates the light from the other mark. This light is reflected by penta-prisms 93 at the viewing points of the instrument into the range finder system and is reflected back by porro prisms 94 positioned in the comparison planes. The beams are finally brought to focus by the lenses 92 forming images 101. By means of total reflecting surfaces 95, prisms 96, relay lenses 97, prisms 98 and eyepieces 99, these images 101 may be viewed stereoscopically by an auxiliary observer. The marks 91 are in the form of transparent slits in

silvered surfaces. Light from the silvered area is reflected back through the semi-transparent surface so that it is viewable directly by the auxiliary observer. The mark 91 thus appears as a dark line on a bright ground, whereas its image appears as a bright line on a dark ground. This is shown in Fig. 7B.

In Fig. 8 the left-hand object beam is received by mirrors 120 and 128 and is brought to focus by a symmetrical lens 122 to form an image in the comparison plane 124. The right-hand object beam is reflected by a single mirror 121 and is reflected and focused by a semi-transparent reflector 123 symmetrically located in the lens 122. Two object images are viewed through an eyepiece 125. They may be brought into coincidence by adjustment of the light deviator 132. Light from a lamp 126 is reflected by a prism 127 illuminating a fiducial mark, and this light is collimated by the lens 122, is reflected by the mirror 128 and a bevel edge 129 on the mirror 120 to strike a bevel edge 130 on the mirror 120. It is again reflected by the semi-transparent surface 123 and finally by a dihedral reflector 131 back along the whole of its path to come to focus forming an image 137 in the comparison plane 124. This image 137 falls between two parts of a comparison mark 136 as long as the instrument is in adjustment. If it gets out of adjustment this may be corrected by a zero adjuster in the form of a screw 133 for deviating the mirror 121. As long as the instrument is in proper adjustment the calibration of the light deviator 132 is correct.

Fig. 9 is similar to Fig. 4 but shows a combination of the invention with that shown in Case M of this series so that the resulting sensitivity is four times normal. In Fig. 9 light from lamps 140 is reflected by prisms 141 to make the round trip through the range finders optical system and back again after reflection at porro prisms 142. This light comes to focus to form images 143' adjacent to the original images 143. The instrument is known to be in adjustment when the apparent image distance of the images 143' appears to be the same as the apparent element distance of the elements 143.

Figs. 10, 10A and 11 show a combination of the present invention with that described in Case N of this series particularly when applied to a coincidence range finder of the type shown in Fig. 1. As particularly shown in Fig. 11, the original element 150 or at least the light therefrom is split into two by a beam splitter 145 covering the upper half of the mark 150. The double light beam then makes the round trip and is reflected back through the system by a porro prism 146 to come to focus in the comparison plane 124. This double light beam is picked up by a dihedral reflector 147 one surface of which 152 is semi-transparent. One of the beams is reflected by one roof surface of the dihedral reflector and the other is transmitted through the surface 152 and is totally reflected by reflector 151 and then reflected by the surface 152 parallel to the other beam. As long as the instrument is in adjustment these two beams are in coincidence. Both beams are reflected by the surface 153 to the eyepiece 25. Any maladjustment of the instrument affects the outgoing pair of beams and similarly affects the returning pair of beams to give double sensitivity. The dihedral reflector pick-up system consisting mainly of the porro prism 147 again doubles the sensitivity since the relative movement of the two beams is twice that

of either beam alone. Thus, the resultant sensitivity is four times normal.

Fig. 11A shows an alternative embodiment in which both the upper and lower halves of the mark 150 are deviated by rhombs 145 and 154 respectively.

In Fig. 12 is shown an embodiment of the invention applied to short-base range finders particularly applied to pure autocollimation as distinguished from range correction setting. These features are alternative in most embodiments of the invention. In this Fig. 12 the viewing point mirrors 160 and 161 send light through a lens 162 into focus in a comparison plane 163 to be viewed through an eyepiece 164. Light from a lamp 165 illuminates a mark 166 and this light is collimated by the objective 162, is reflected by an auxiliary reflector 167 on the mirror 160 and is then reflected by a prism 168, equivalent to a dove prism, rigidly attached to the mirror 161. This light is brought to focus by the objective 162 approximately in the comparison plane 163 whereat it is reflected by a porro prism 169 back through the whole optical system eventually to form an image 166' at the comparison plane 163, which image acts as an index for a scale 171 engraved in the comparison plane. The double sensitivity feature in this case permits the scale 171 to be larger, and hence, more easily read. Coincidence of the object images is obtained by adjustment of a light deviator 170 operating on the mirror 160. Anything which affects the coincidence of the object images, similarly affects the position of the image 166' relative to the scale 171.

Figs. 13, 13A and 13B show a form of the invention applied to stereo range finders having some elements similar to Fig. 5. The elements peculiar to this arrangement include a lamp 176 and a prism 177 by which a coincidence line and fiducial mark each consisting of a spiral 179 on a disk 178 are illuminated. Light from these adjustment coincident elements 179 is collimated by lens 180 and one half of it is reflected by a mirror 181 through lens 71 to a porro prism 184 in the comparison plane 52 and thence back through the objective 71 which collimates the light again. The collimated beam is then reflected by a mirror 182 to an objective 185 which brings it into focus in an auxiliary comparison plane 186 to form an image 179'. The other beam is first reflected by the mirror 182 to the left-hand viewing point and by penta prisms 183, from one viewing point to the other and into the right-hand half of the range finder. The beam is then reflected by a porro prism 184 in the right-hand comparison plane back around the system until it strikes the mirror 181 which reflects it to the lens 185 and eventually into focus to form the other image 179'. The main observer varies the apparent object distance, by means of a light deviator 175, to match some standard reticle, not shown. At the same time the auxiliary observer rotates the disk 178 until the images 179' as shown in Fig. 13A are brought into coincidence. At this time the range may be read from a scale 187 against an index 188, the scale and index being operated by the disk 178.

The arrangement shown in Figs. 14, 15 and 16 is directly applicable to various forms of the invention and may be used in either Fig. 1 or Fig. 4. This arrangement gives the advantages of a coincidence line and fiducial mark system and in Fig. 1 gives the double sensitivity due to the

present invention. Considering it first in connection with Fig. 1, a field lens or other unit 190 is placed in the comparison plane 24 to be rotatable about its center, approximately at which point is rotated the apex of a triple mirror 194, rigidly mounted to rotate with the element 190. Light from a lamp 191 reflected by a semi-transparent surface 198 illuminates spiral 192 engraved on the element 190 and this light makes the round trip shown in Fig. 1 until it strikes the triple mirror 194, which replaced the porro prism 35 of Fig. 1, whereat it is reflected back around the whole optical system to form an image 195 adjacent to the spiral 192. Both the spiral, or at least the illuminated portion thereof, and the image 195 are viewable through the eyepiece 25. When the object images are brought into coincidence by a light deviator at the position of the zero adjuster 38, the light deviator 26 being eliminated in a coincidence line system, the disk or element 190 is rotated until the image 195 and line 192 are in coincidence, at which time the range may be read by a scale 196, carried by the element 190, against an index 197.

The same is true when the element 190 is substituted for the element 52 of Fig. 4. That is, the light deviator 68 is no longer necessary and is replaced by one at the position of the zero adjuster 69, the range being given by a scale 196 operated by the coincidence line 192. Attention is drawn to the fact that the fiducial mark for the coincidence line 192 is the image of the line itself and this is made possible by the use of the present invention consisting of a triple mirror 194 (replacing 35 in Fig. 1 and cooperating with 65 in Fig. 4) in the other comparison plane. Further, the triple mirror 194 is rigidly attached to the coincidence line 192 so no error can be introduced by looseness in the bearings supporting element 190. This is of course of greatest value in the coincidence type range finder in Fig. 1, but in Fig. 4 it gives four times sensitivity instead of double sensitivity since two reflectors, namely, 194 and 65, both operate on the element light beam.

What I claim and desire to secure by Letters Patent of the United States is:

1. A range finder of the type having two horizontally spaced viewing points at which beams of light are received from the object being ranged, an optical system for focusing the object beams to form images in comparison planes and a ranging adjustor operating effectively horizontally, said range finder being characterized by a pair of adjustment coincident elements and means for projecting at least twice through said optical system a light beam from one of the elements to form an image thereof adjacent to at least an image of the other element, said projecting means including a reflector with at least two reflecting surfaces at one comparison plane for receiving the element beam, and for reflecting it back through the optical system to the other comparison plane.

2. A range finder according to claim 1 in which said projecting means includes another reflector with two reflecting surfaces at the other comparison plane so that the element beam traverses the optical system at least three times.

3. A range finder according to claim 1 and of the coincidence type in which the comparison planes are coplanar.

4. A ranger finder according to claim 1 in which the adjustment coincident elements are a fiducial mark and coincidence line respectively.

5. A range finder according to claim 1 in which both elements are in the same comparison plane and the element beam traverses the optical system an even number of times.

6. In an autocollimating range finder of the type in which an image of one adjustment coincident element is formed adjacent to another by light traversing the optical system of the range finder, the subcombination of a pair of reflecting surfaces at one comparison plane of the range finder for receiving said light, for displacing it effectively horizontally and for reflecting it back through said optical system to the other comparison plane.

7. A range finder according to claim 1 in which said reflector is a right angle porro prism with its roof edge in said one comparison plane.

8. The subcombination according to claim 6 in which said pair of reflecting surfaces are the sides of a porro prism with its roof edge in said one comparison plane.

9. A range finder according to claim 1 in which said reflector is a triple mirror system with its apex in said one comparison plane.

10. In an autocollimating range finder of the type in which an image of one adjustment coincident element is formed adjacent to another by light traversing the optical system of the range finder, the subcombination of a triple mirror at one comparison plane of the range finder for receiving said light, for displacing it effectively horizontally and for reflecting it back through said optical system.

11. A ranger finder of the type having two horizontally spaced viewing points at which beams of light are received from the object being ranged, an optical system for focusing the object beams to form images in comparison planes and a ranging adjustor operating effectively horizontally, said range finder being characterized by a pair of adjustment coincident elements, means for projecting through the optical system a light beam from each element to form an image approximately in each comparison plane respectively, a reflector with at least two reflecting surfaces at each comparison plane for receiving each beam, for displacing it effectively horizontally and for reflecting it back through the optical system to form relayed element images and means for viewing the relayed images relative to one another.

12. A range finder according to claim 11 in which the relayed images and the elements are all viewed stereoscopically to give apparent element and image distances.

13. A ranger finder of the type having two horizontally spaced viewing points at which beams of light are received from the object being ranged, an optical system for focusing the object beams to form images in comparison planes and a ranging adjustor operating effectively horizontally, said range finder being characterized by a pair of adjustment coincident elements and means for projecting through at least half of said optical system a light beam from one of the elements to one of the comparison planes and back through said at least half of the optical system to form an image of the element for comparison with at least an image of the other element, said projecting means including a reflector with at least two reflecting surfaces at said one of the comparison planes for receiving said beam, for displacing it effectively horizontally and for reflecting it back.

14. A ranger finder according to claim 13 in

which said one of the elements it at last optically in the other comparison plane and the projecting means includes the whole of the optical system.

15. A range finder according to claim 13 in which said projecting means includes only said half of the optical system and a similar projecting means is in the other half of the optical system to form an image of the other element for comparison with the image of the first mentioned element.

16. A range finder according to claim 13 including another reflector with two reflecting surfaces for receiving the reflected beams, for

displacing it again effectively horizontally and for reflecting back through said at least half of the optical system for a third trip therethrough.

17. A ranger finder according to claim 13 in which the elements are at least optically in the comparison planes and in which said projecting means includes another reflector with at least two reflecting surfaces similarly positioned at the other comparison plane, said element light beam traverses the whole optical system at least three times and said one element image is formed adjacent to the other element itself.

STEPHEN M. MACNEILLE.
